UNITED STATES PATENT OFFICE.

EDWARD H. PALMER, OF DETROIT, MICHIGAN, ASSIGNOR OF ONE-HALF
TO EFFIE A. WIGGIN, OF SAME PLACE.

INCANDESCENT LAMP.

SPECIFICATION forming part of Letters Patent No. 655,158, dated July 31, 1900.

Application filed January 5, 1900. Serial No. 427. (No model.)

To all whom it may concern:

Be it known that I, EDWARD H. PALMER, a citizen of the United States, residing at Detroit, county of Wayne, State of Michigan, have invented a certain new and useful Improvement in Incandescent Lamps; and I declare the following to be a full, clear, and exact description of the invention, such as will enable others skilled in the art to which it pertains to make and use the same, reference being had to the accompanying drawings, which form a part of this specification.

This invention relates to lamps, and has for its object an improved burner arranged to produce gas and burn the gas, using the burning gas to render incandescent a mantle that is properly suspended above the burner.

In the drawings, Figure 1 is a sectional elevation of the burner. Fig. 2 is a cross-section of the mixing-chamber of the burner. Fig. 3 is an elevation of an initial generating-lamp. Fig. 4 is a perspective of the wick-tube of the generating-lamp.

The lamp receives its supply of hydrocarbon in the form of gasolene from a tank properly situated with respect to it and from which the gasolene is led through the pipe 2 to a generating-chamber 3. This generating-chamber is a vertical tubular chamber extending vertically along the mixing-chamber 4 and preferably inside the mixing-chamber, leaving the outside of the mixing-chamber cylindrical. The tube 3 is made by thickening the wall of the mixing-chamber and boring into the thickened part of the wall to form the tubular chamber. The thickened wall in which the generating-chamber is made extends below the lower shoulder 5 of the mixing-chamber and along the outside of the reduced or stem part 6 of the mixing-chamber, extending below a coupling-neck 7, where the feed-pipe 2 is coupled to the burner. Below the coupling 7 the bore of the tubular upright part decreases in size and extends with this diminished size through a hanging tube 8, that reaches through to a valve-chamber 9. From the valve-chamber 9 there is an opening 10 to a second valve-chamber 11, in which there is a regulating-valve 12, actuated by a

thumb-nut 13. The regulating-valve 12 is a 50 needle-valve, the point of which engages in a seat 14, through which there is an opening, the size of which is regulated by the needle-valve, and the opening directs the gas directly upward into and through the mixing-chambers 6 and 4. Into the reduced bore of the tube 8 is screwed a small vertical tube 16, that reaches up on the inside of the generating-chamber 3, preferably coaxially with said chamber, and terminates near the top with 60 an open mouth. The top of the generating-chamber 3 is closed, and all gas generated in this chamber is compelled by its own pressure to travel downward through the small tube 16, by the valve 9, through the opening 10, 65 through the regulating-valve chamber, and out through the opening 14 into the mixing-chamber, where it mingles with air that is drawn into the mixing-chamber through the holes 17. The mingled air and gas rises to 70 the top of the mixing-chamber 4 and escapes from the mixing-chamber through a grating 18 into the combustion-chamber under the mantle 19, and burning under the mantle heats the mantle to a white heat, producing 75 what is known as an "incandescent light."

As is well known, the attempt to burn gasolene before it has been converted by heat into gas is attended with a production of considerable smoke and soot, and to prevent this I 80 convert the gasolene into gas before igniting it by means of an initial-lighting device, which consists of a small alcohol-lamp 20. The alcohol-lamp has a burner, preferably fitted for a flat wick that rises some distance 85 above the neck of the lamp and is open at the top and along one side from near the neck of the lamp to the top of the burner. The edge of the flat wick reaches out through the opening along the side of the flat burner and 90 a flame is produced that extends along the entire vertical length of the open part of the wick-tube, furnishing a large heating-flame from a comparatively-small tube. This lamp is preferably made with a hook *h*, by means 95 of which it is hung to the feed-pipe 2 in position to properly heat the generating-chamber 3, and as soon as this generating-chamber

ber has been properly heated and gas begins to form in quantities sufficient to burn and heat the mantle properly the generating-lamp is removed or can be removed and used for 5 other lamps or set aside.

The mantle is supported in the ordinary way by a standard that rises from a ring which surrounds the mixing-chamber and furnishes a rest for the protecting-chimney used with 10 burners of this class.

After the flame has been properly started the generating-chamber 3 is heated by the flame in the combustion-chamber, and the supply of gas is kept up so long as fuel is 15 supplied and the valves are left open. The closing of either of the valves 9 or 13 instantly stops the combustion. The cylindrical chamber or tube 3, with its coaxial gas-tube 16, forms an annular generating-chamber which 20 presents a large surface to the heat with a comparatively-small volume of gasoline.

What I claim is—

In an incandescent lamp, in combination with a hollow mixing-chamber, a semicylindrical lug parallel to the axis of said chamber 25 forming a part of the walls, and extending into the hollow thereof, said lug being hollowed out longitudinally and having its upper end closed and its lower end communicating with the hydrocarbon-reservoir, a vertical tubular gas-conductor approximately concentric with said hollow in said lug, said gas-conductor leading from the top of said hollow downward, and communicating with the mixing-chamber, substantially as de- 30 scribed.

In testimony whereof I sign this specification in the presence of two witnesses,

EDWARD H. PALMER.
